(57) **CLAIM**

The ornamental design for a portion of a handheld electronic device, as shown and described.

DESCRIPTION

FIG. 1 is an enlarged first perspective view of a portion of a handheld electronic device, showing a first embodiment of our new design;

FIG. 2 is an enlarged second perspective view thereof;

FIG. 3 is a rear view thereof;

FIG. 4 is a top view thereof;

FIG. 5 is a front view thereof;

FIG. 6 is a side view thereof, the other side view thereof being a mirror image;

FIG. 7 is a bottom view thereof;

FIG. 8 is a side view of the portion of a handheld electronic device in a state of use;

FIG. 9 is a perspective view thereof;

FIG. 10 is an enlarged first perspective view of a portion of a handheld electronic device, showing a second embodiment of our new design;

FIG. 11 is an enlarged second perspective view thereof;

FIG. 12 is a rear view thereof;

FIG. 13 is a top view thereof;

FIG. 14 is a front view thereof;

FIG. 15 is a side view thereof, the other side view thereof being a mirror image;

FIG. 16 is a bottom view thereof;

FIG. 17 is a side view of the portion of a handheld electronic device in a state of use; and,

FIG. 18 is a perspective view thereof further.

The broken lines depict portions of the portion of a handheld electronic device which form no part of the claimed design.

Unshaded surfaces bound by broken lines form no part of the
